Attorney.

UNITED STATES PATENT OFFICE.

WALKER BOOTH, OF COLLINGSWOOD, NEW JERSEY.

STYLUS-HOLDER.

1,287,199.

Specification of Letters Patent. Patented Dec. 10, 1918.

Application filed November 7, 1917. Serial No. 200,800.

To all whom it may concern:

Be it known that I, WALKER BOOTH, a citizen of the United States, residing at 614 Frazer avenue, Collingswood, in the county 5 of Camden and State of New Jersey, have invented new and useful Improvements in Stylus-Holders, of which the following is a specification.

The invention relates to soundboxes, such 10 as used in connection with phonographs or other talking machines, and has for an object to provide a holder for the stylus of the soundbox.

The invention comprehends among other 15 features, the provision of a simple holder for securing the free end of the stylus arm with relation to the soundbox proper, the invention being of a form which will enable the same to be made very cheaply, and readily applied, and also permit of securing the stylus arm to the desired degree of rigidity, so that the most effective sound results can be obtained, and whereby further adjustment of the connection can be obtained.

25 In the further disclosure of the invention, reference is to be had to the accompanying drawing, constituting a part of this specification, and in which similar characters of reference denote corresponding parts in all 30 the views, and in which—

Figure 1 is a side elevation of the soundbox showing my device applied thereto.

Fig. 2 is a face view of the structure shown in Fig. 1.

35 Fig. 3 is a bottom plan view, and

Fig. 4 is a fragmentary bottom plan sectional view showing mechanical details.

Referring more particularly to the views, 10 indicates a soundbox having the usual diaphragm 11, to the center of which one end 40 of the usual stylus 12 is secured, said stylus projecting parallel to the face of the diaphragm and beyond the edge thereof, and adapted to receive the usual sound needle 13 secured by the usual screw 14. In order to 45 secure the free end of the stylus arm rigid with respect to the soundbox 10, I provide a holder or support which in its entirety is indicated by the numeral 15, and which in 50 detail embodies a T-shaped plate 16 secured to the under side of the soundbox 10 by a threaded stud or projection 17, which is formed with and extends through a tubular internally threaded sleeve 18, said stud being 55 threaded through the plate 16 and into the

soundbox, thus rigidly securing the plate to the soundbox, and also positioning the sleeve with respect to the plate, said sleeve extending at right-angles to a projecting part 19 of the plate. A threaded pin 20 serves as 60 the fulcrum or pivotal point for a pair of arms 21 in the nature of toggles, of a scissors-like construction, having their forward pointed ends 22 projecting into recesses 23 formed in the stylus arm 12, the rear ends 65 of said arms being provided with transverse openings 24 through which are loosely passed suitable adjusting screws 25, threaded into the sleeve 18.

From the foregoing it will be seen that 70 the various parts described can be readily assembled, and it will be clear that when the screws 25 are screwed up into the cylinder 18, it will force the forward pointed ends 75 21 of the arms into positive and absolute engagement with the stylus arm by extending into the recesses 22, and as the screws are tightened up, a rigid connection between the stylus arm and the soundbox will be assured. It will be clear also that the particular 80 holder or connection, provides for an adjustment so that the desired rigid connections between the free end of the stylus arm and sound box can be varied and easily 85 adjusted by tightening or loosening the screws 25.

It will be understood that I do not limit myself to the particular form of construction shown; that various slight changes may be made, without departing from the 90 spirit of the invention, the scope of which is defined in the appended claims.

I claim:

1. A holder for the stylus of a soundbox comprising a plate secured to the soundbox, 95 pivoted arms supported on the plate and having their forward ends for engagement with the free end of the stylus arm, a sleeve interposed between the rear ends of said arms, and screws passing through the rear 100 ends of the arms and engaging with the sleeve, whereby the rear ends of said arms can be moved toward each other to insure a rigid connection between the forward ends of the arms and the stylus. 105

2. A holder for the stylus of a soundbox comprising a plurality of crossed pivoted arms movably supported on the soundbox, with the front ends of the arms engaging the stylus, and means for moving the rear 110

ends of said arms toward each other to insure rigid connection between the stylus and front end of said arms.

3. A holder for the stylus of a soundbox comprising a plate on the soundbox, a plurality of toggle arms pivoted on the plate, with the forward ends of said arms engaging the stylus, a sleeve, a stud on the sleeve and threaded on to the plate to support the sleeve thereon, and screws passing through the rear ends of the arms and in threaded connection with the sleeve, whereby when said screws are tightened, with respect to

the sleeve, the forward ends of the arms will be rigidly engaged with the stylus. 15

4. In a device of the character described, a soundbox having a stylus, a support carried by the soundbox, crossed arms pivoted to the support, and means operating on one of the ends of said arms to clamp the opposite ends of said arms against the stylus. 20

In testimony whereof I affix my signature.
WALKER BOOTH.

Witnesses:

DANIEL CAMERON,
Mrs. WALKER BOOTH.
